Inventor:

Robert Edwin Reardon

UNITED STATES PATENT OFFICE.

ROBERT EDWIN REARDON, OF COLUMBIA, PENNSYLVANIA.

REPEATING TOY FIREARM.

Application filed February 14, 1924. Serial No. 692,709.

To all whom it may concern:

Be it known that I, ROBERT EDWIN REARDON, a subject of the King of Great Britain, residing in the town of Columbia, county 5 of Lancaster, and State of Pennsylvania, United States of America, have invented a new and useful Repeating Toy Firearm, of which the following is a specification.

My invention relates to improvements in 10 toy firearms, particularly those of the cap tape fed, repeating pistol type that are operated by trigger pressure. The object of my invention is to simplify the construction and lessen the cost of production of such devices without impairing their operative effectiveness. My improvement is herein presented in the form of a trigger-pressure operated toy pistol having an operating mechanism comprised of two members only, 15 which with three springs and the pistol casing parts perform the functions of cap tape feeding and firing usually performed by a greater number of parts, often with less efficiency. The manufacturing advantage of 20 having fewer parts to make and handle is obvious. Another improvement in toy pistols of this type lies in a straight pull trigger operation, which increases the resemblance of the toy to a real automatic pistol. 25 A further improvement is in operating means whereby the hammer, which is normally retracted from the anvil, strikes the anvil and returns to normal while the trigger is being retracted.

30 I attain the object of my invention by the construction, combination and arrangement of parts hereinafter described and particularly pointed out in the claims, it being understood that I do not intend to limit myself to the details of construction or combination of the various parts as described and shown herein.

35 My invention is illustrated in the accompanying drawings in which:

40 Figure 1 is a side elevation, interior view, of the left side of the casing of my toy automatic pistol showing the operating parts therein in normal position as ready for loading with a roll of explosive cap tape.

45 Figure 2 is a side interior view of the left side of the casing of my toy pistol with the operating parts therein, a roll of cap tape being in place and the trigger member partially retracted and hammer depressed 50 thereon.

55 Figure 3 is a side interior view of part of

the left side of the casing of my toy pistol with the operating parts therein, showing the trigger member fully retracted with its forward end shielding rear of anvil, as after 60 firing operation of the hammer and return of same to normal position.

Figure 4 is a side exterior view of the right side of the casing of my toy pistol.

Figure 5 is a side exterior view of the 65 door plate of my toy pistol.

In the drawings like numerals indicate similar parts.

The pistol as shown is preferably made of cast iron or other metal which may be 70 molded. The casing side A bears, extending right angularly therefrom, an anvil wall A¹; a forwardly sloped, operating spring releasing and trigger member guiding ridge A²; an operating spring post A³; 75 a spring bearing and trigger tilting post A⁴; a door plate pivot post A⁵; and a cap roll post A⁶. It also has a trigger spring recess A⁷; a hammer pivot hole A⁸; and assembly rivet hole A⁹; an anvil cap recess 80 A¹⁰; and an anvil cap-retainer ridge A¹¹. A squared base on the operating spring post A³, which serves to elevate the said spring on the post and guide the trigger member, is denoted by A¹². The casing side B, the 85 right half of the pistol body, has an assembly hole arm B¹; a rivet hole B² therein; a depressed section B³ which coincides in plane with casing side A of the pistol; and a trigger pivot hole B⁴. The door plate C 90 of the pistol completes the right side casing. It is mounted by means of a foresight-forming flange C¹ with a pivot hole C² therein on a pivot post A⁵ of casing side A, being rotatably held thereon by casing 95 side B when the pistol is assembled.

The hammer D of my pistol is pivoted by integral hubs D¹ in pivot holes A⁷ and B⁴ of the casing sides A and B respectively. From the under side of hammer D extends 100 downwardly a flange D² which engages an operating spring F that is mounted on post A³ of casing side A. The angularly flanged nose D⁴ of said flange D² abuts a double arm F¹ of the operating spring F while a 105 hole D⁵ in flange D² engages a second arm F² of said operating spring F which is an approximately right angular extension of one of the arms comprised in double arm F¹. A third arm F³ of the operating spring F 110 bears upon the upper side of post A⁴ of casing side A, thereby normally elevating

the head D² of hammer D against marginal flange A¹² of casing side A, as shown in Figure 1, by controlling through double arm F¹ that arm itself and its arm F² of said 5 operating spring F. The lower end of said double arm F¹ of the spring F rests normally upon the foot of the slope of the forwardly sloped ridge A² of casing side A, across a rearward extension E⁷ of a trigger 10 member E and facing the end of a thrusting ridge E⁶ extended right angularly from said rearward extension E⁷, longitudinally of same, and in vertical height lower than sloped ridge A² which it adjacently parallels. 15 A marginal flange E⁸ which approximates in length the interior distance between casing sides A and B when the pistol is assembled, extends right angularly from the rear end of extension E⁷ of the trigger member E, and prevents undue lateral movement of the trigger member, thus maintaining the proper relation between the sloped ridge A² of casing side A and the spring thrusting ridge E⁶ of trigger member E. The trigger 20 member E has a tape guiding wall E¹ the upper end of which normally covers the anvil A¹ and is thickened thereover to form a hammer head runway and tilting ridge E². From the lower end of tape wall E¹ 25 projects a nub E³ which engages one end of a coiled trigger retracting spring G, the other end of said spring being set in a recess A⁶ in casing side A. The lower forward edge of trigger member E forms a 30 finger grip E⁹. The trigger returning spring G bears upon the trigger member E below the horizontal center of finger grip E⁹, thus tending to tilt upward the loose forward end of the trigger member and raise 35 tape wall E¹ from contact with anvil ridge A¹⁰ as the trigger returns after firing. When the trigger is being pressed back by 40 pressure on grip E⁹, resistance of double arm F¹ of operating spring F to the thrust 45 of ridge E⁶ of trigger member E, being applied well above the center of finger grip E⁹, tends to tilt the trigger member downward forward and increase the pressure of tape wall E¹ on anvil ridge A¹⁰. This 50 pressure is supplemented by the hammer head D² bearing down on the upper side of tape wall E¹, on the runway ridge E². Facing the inner side of the lower end of wall E¹ 55 is projected from the body of trigger member E a feed spring bearing post E³, forming a corner post on the tape pathway thereat. Adjacently below said post and parallel thereto stands a semi-circular post with a V-shaped groove in one side which 60 forms a bearing and stop for a tape feed spring H, by engaging the bent lower end of said spring in said groove. This spring H while broadly termed a feed spring is 65 specifically a brake spring or resilient clamp and detent pawl which holds the cap tape T against the tape wall E¹ of trigger member E so that it moves forward therewith over anvil ridge A¹⁰ without undue loss of motion, the actual feeding being done by the retraction of trigger member wall E¹ over 70 said anvil ridge A¹⁰, with the cap tape between said wall and ridge. The upper end of the said feed spring H bears against the tape wall E¹ slightly below the tape advancing plane of same along which the cap tape passes approximately horizontally over the anvil A¹. It may be noted that when the door plate C of my pistol is swung back the entire pathway of the cap tape, from cap roll post A⁶ to the spent tape exit at the 75 outer end of anvil A¹, is thrown open, thereby facilitating loading or cleaning or any required adjustment. The upper edge of the rearward extension E⁷ of trigger member E is cut away, sloping forwardly, to the junction of the extension E⁷ with tape wall E¹, so that when the trigger member E is retracted to the limit and ridge E² on top of tape wall E¹ abuts tilting post A⁴ of 80 casing side A, as in Figure 3, the said rearward extension E⁷ tilts upward around the base A¹¹ of operating-spring post A³, departing from its normal horizontal pathway between said post base A¹¹ and sloped ridge A² of casing side A, and allows the 85 forward end of tape wall E¹ to tilt downward over anvil ridge A¹⁰ and anvil recess A⁹ upon the surface of the anvil A¹, thus 90 shielding against backfire the cap following immediately the cap exposed to the hammer blow. 95

The operation of my toy pistol is effected as follows. A roll of explosive cap tape is placed on post A⁶ and the free end of the tape, preferably with caps facing forwardly, is passed upward along the face of tape wall E¹ between the free end of feed spring H and said wall and the anvil A¹ and said wall, placing the foremost cap, as T¹, in position on the anvil. The following cap, as T², will then lie in anvil recess A⁹, adjoining the anvil ridge A¹⁰, and the third cap, as T³, Figure 2, will lie adjacent the free end of feed spring H, in advance of same. The fourth cap, as T⁴, will lie underneath the free end of the feed spring H. The door plate C being closed, the trigger member E is retracted, by finger pressure upon the finger grip E⁹, against the pressure of double arm F¹ of operating spring F upon the end of ridge E⁶ of the trigger member and the additional pressure of trigger returning spring G upon the lower end of tape wall E¹ and nub E³ thereon. The resistance of the upper spring, the double arm F¹ of operating spring F, being the stronger, the finger pressure pulls downward upon the anvil ridge A¹⁰ the forward end of tape wall E¹, pressing the cap tape T upon said ridge so strongly that 100

105 110 115 120 125 130

the cap T^2 in advance of said ridge is held against withdrawal over same, remaining in anvil recess A^9 . As the trigger member E retracts, the thrust of ridge E^6 against the 5 double arm F^1 of the operating spring F , causes that spring to rotate on its pivot post A^3 and correspondingly depress with increasing pressure against the upper side of tape wall E^1 , whereon is the hammer runway and tilting ridge E^2 , the head D^2 of hammer D , by means of the engagement therewith in hole D^3 of flange D^3 of the 10 right angular arm F^2 of the operating spring F . When the trigger member has retracted 15 to proper distance the tape wall E^1 rides clear of engagement with hammer head D^2 , and the hammer strikes forcibly upon the anvil A^1 and the explosive cap T^1 in place thereon. Immediately following this action 20 the retraction of the thrust ridge E^6 against double arm E^1 of the operating spring F , which has been forcing said double arm F^1 up the slope of the sloped ridge A^2 on which it rests, reaches a height 25 on said slope which equals or exceeds its own height and the said spring arm F^1 rides clear of the thrust ridge E^6 and flies back against the angularly flanged nose D^4 of the flange D^3 of the hammer D , the arm F^2 of the 30 operating spring F flying upward simultaneously, in engagement with hammer D by means of hole D^5 in flange D^3 , as the operating spring F is rotated to normal on its pivot post A^3 by the pressure of arm F^3 of said spring upon its bearing post A^4 . The hammer D thus returns to normal position 35 immediately after striking the anvil, A^1 . Simultaneously with the release of the hammer D to strike the anvil A^1 and the release of spring arm F^1 , the tilting ridge E^2 of tape wall E^1 rides against the tilting post A^4 of casing side A , thereby tilting the forward end of tape wall E^1 downward 40 over the anvil ridge A^{10} and its adjacent recess A^9 and shielding the second cap, as T^2 , against brackfire from the explosion of the foremost cap, T^1 , on the anvil, A^1 , as in Figure 3. The returning action of trigger spring G then, finger pressure being 45 slackened, returns the trigger member E to normal position, the tape wall E^1 riding loosely over the anvil ridge A^{10} , because of the sub-finger pressure of the spring G on the trigger member tending to elevate 50 or tilt the forward end of the tape wall away from the anvil. As the trigger member E reaches its forward limit the upwardly extending rear section of rearward extension E^7 of the said trigger member, denoted by E^{10} , abuts a downward projection A^{12} of the squared base of operating spring pivot post A^3 , which engagement by continued action of trigger spring G brings the trigger member E to rest in normal position 55 with the tape wall E^1 raised clear of

the anvil, in very convenient position for loading when necessary. This operating action may be repeated as required.

I claim:

1. In a toy firearm, a body, a transversely ridged anvil, a spring hammer, and a spring retracted, horizontally movable, tape carrying trigger member adapted to engage an explosive cap tape with said anvil ridge when the said trigger member recedes from the 75 anvil and advance said tape freely across said anvil when the trigger member returns to normal position.
2. In a toy firearm, a body, an anvil, a spring hammer, a horizontally movable, tape carrying, spring retracted trigger member, means for relatively advancing an explosive cap tape upon said trigger member by recession of said trigger member from normal 80 position, means for percussing said hammer upon said anvil by recession of said trigger member, means for shielding part of said anvil while the hammer percusses upon another part, means for releasing percussive 85 spring pressure upon said hammer and reTRACTING said hammer from the anvil while the trigger member is receding from said anvil, and means for advancing the explosive cap tape across the anvil as the trigger member reTRACTS to normal position. 90
3. In a toy firearm, a body, an anvil, a spring hammer normally held away from said anvil, a spring returned trigger member, and means for percussing said hammer upon the said anvil and reTRACTING it therefrom while the trigger member is receding. 100
4. In a toy firearm, a body, an anvil, a spring hammer, and a trigger member horizontally movable across said anvil and terminally contacting upon same when at limit 105 of movement in one direction and clear of said anvil when at the limit of movement in the opposite direction.
5. In a toy firearm, a body, an anvil, a hammer, and a horizontally movable trigger 110 an integral portion of which is adapted to slide over and upon said anvil.
6. In a toy firearm, a body, an anvil having a transverse ridge thereon, and a horizontally movable trigger member adapted 115 to slide over said anvil and abrade upon said transverse ridge on said anvil.
7. In a toy firearm, a body, an anvil, a hammer, a horizontally movable trigger, and means for shielding a section of said 120 anvil with an integral portion of said trigger.
8. In a toy firearm, a body, an anvil, a hammer, a trigger member adapted to carry explosive cap tape, and means for relatively 125 advancing explosive cap tape on said trigger member by recession of said trigger member from normal position.
9. A trigger pressure operated, repeating cap tape feeding and firing mechanism that 130

- is limited in constituent parts to a casing, a hammer, a horizontally movable trigger member, an operating spring, a trigger returning spring and a pawl spring.
- 5 10. In a toy pistol, a body, an anvil, a hammer, and a straight pull trigger for directly carrying an explosive cap to said anvil.
11. In a toy firearm, means for feeding 10 and detonating explosive cap tape consisting only of a casing, a hammer member adapted to strike within the path of a trigger member, a trigger member movable across the path of said hammer member and accessory springs.
12. In a toy firearm, straight pull means 15 for feeding and detonating explosive cap tape consisting only of a casing, a hammer
- member, a trigger member movable to impede or actuate said hammer member and 20 accessory springs.
13. In a toy firearm, an anvil, a trigger member, a hammer member adapted to strike upon said anvil by trigger pressure actuated means, and self-acting means where- 25 by said hammer is normally held away from said anvil.
14. In a toy firearm, an anvil, a hammer adapted to strike the anvil but normally separated therefrom, a trigger member, and trigger pressure actuated means for feeding detonative material to said anvil, and causing the hammer to momentarily strike upon 30 said anvil.

ROBERT EDWIN REARDON.
